Bradley D. Johnson(57) **CLAIM**

We claim the ornamental design for an external rearview mirror, as shown and described.

DESCRIPTION

FIG. 1 is a front top perspective view of an external rearview mirror of the present disclosure;

FIG. 2 is a rear top perspective view of the external rearview mirror of FIG. 1;

FIG. 3 is a front side perspective view of the external rearview mirror of FIG. 1;

FIG. 4 is a rear side perspective view of the external rearview mirror of FIG. 1;

FIG. 5 is a front elevational view of the external rearview mirror of FIG. 1; and,

FIG. 6 is a rear elevational view of the external rearview mirror of FIG. 1.

The broken line surrounding the interior of the rear views of the external rearview mirror is a boundary between the claim and environmental material. The broken line and area within it form no part of the claimed design.
